ABSTRACT OF THE DISCLOSURE

The shock of releasing toggle pliers is reduced by cushion bumpers on the release lever which take effect when the toggle links reach the opening side of dead center. The effect is a two stage release where the heavy pressure is dissipated before the parts are allowed to move to the full open position. In a preferred form, the bumper of the release lever is squeezed against the actuating lever which comprises one of the toggle links.

This invention is intended to improve the operation of toggle or vise grip pliers by the use of appropriately arranged cushion bumpers to reduce the shocks which accompany release of the gripping pressure. In a preferred form where the release is effected by a release lever which is squeezed against the actuating lever, the cushion bumper is arranged between the release and actuating levers and in effect results in a two stage opening of the pliers. During the first stage the toggle links move from dead center to the opening side of dead center and the heavy closing pressure of the jaws of the work is released. Since the movement of the jaws at this stage is slight, the momentum of the parts is small even through the pressures which are released are huge. During the second stage, the jaw opening spring moves the actuating lever to its full open position in readiness to receive another work piece.

In the drawing, FIG. 1 is a side elevation of a toggle pliers in the full open position, FIG. 2 is a section on line 2—2 of FIG. 1, FIG. 3 is a side elevation of the pliers in the closed position, FIG. 4 is a view similar to FIG. 2 of a modification, FIG. 5 is a side elevation of another form of toggle pliers in the closed position, and FIG. 6 is a side elevation showing the FIG. 5 pliers with the actuating lever moved to the opening side of dead center.

In the pliers shown in FIGS. 1—4 inclusive, a handle 1 carries a fixed jaw 2 at its front end and has its back end 3 internally threaded to receive an adjusting screw 4 which may be turned by a knob 5. The adjusting screw may be locked in adjusted position by a lock nut 6 which may be tightened against a shoulder 7 on the end 3 of the handle to prevent turning of the adjusting screw. Associated with the stationary jaw is a movable jaw 8 pivoted at 9 on the handle and urged toward the open position by a coil spring 10 stretched between an ear 11 on the handle and an eye 12 on the movable jaw. The handle 1 is conveniently made of channel cross section except at the end 3 where the handle is formed to a curved section so that it may be internally threaded to cooperate with the adjusting screw 4. The channel section permits the major portion of the spring 10 to be housed between the sides of the channel.

Pivoted to the movable jaw 8 is an actuating lever 14 of channel section with its sides straddling the end 15 of a toggle lever 16 extending between a pivot abutment 17 on the inner end of the adjusting screw 4 and a common pivot 18 between the levers 14 and 16. The pivots 13, 17 and 18 together with the intermediate portions of the actuating lever 14 and the lever 16 form a toggle joint which in FIG. 1 is shown in the re-

2

laxed or open position. In order to develop gripping pressure between the jaws 2, 8 and an interposed work piece 19, the hand grip portion 20 of the actuating lever 14 is squeezed toward the handle 1, bringing the pivots 13, 17 and 18 to the dead center or pressure position shown in FIG. 3. Because of the toggle action, huge forces can be developed between the jaws 2 and 8. The dead center position of the toggle is determined by the position of the abutment 17 on the end of the adjusting screw 4. For thick work pieces, the abutment 17 is moved to the right as viewed in FIG. 3, while for work pieces thinner than the work piece 19, the abutment is moved to the left. For repetitive work, it is desirable that once the abutment 17 has been adjusted to the desired position for the particular thickness of work piece, the adjusting screw 4 be locked in place as is conveniently done by the lock nut 6.

In the pressure or gripping position shown in FIG. 3, a projection 21a on the lever 16 bottoms on the bottom wall 22 of the channel section of the actuating lever and a projection 21 on the lever 16 projects through a slot 23 in the bottom wall 22 so that the end 24 of the projection bears against the bottom wall 25 of a channel shaped release lever 26 pivoted at 27 on the actuating lever 14. The release lever 26 straddles the actuating lever 14 and the bottom wall 25 preferably conforms generally to the shape of the bottom wall of the actuating lever. To release the grip of the jaws 2, 8 on the intervening work piece, the hand grip section 28 of the release lever is squeezed toward the outer surface of the actuating lever. This causes the actuating lever 14 to be pivoted in a clockwise direction about the pivot 13. When the actuating lever reaches the position indicated roughly by dotted lines 29, the common pivot or knee 18 of the toggle is moved to the jaw opening side of dead center. At this stage, the clamping pressure between the jaws is substantially released although the jaws have not opened appreciably. When the actuating lever reaches the dotted line position 29, it strikes an elastomeric coating 30 on the hand grip section 28 of the release lever. This cushions the shock. Because of the relatively slight motion, the momentum of the actuating lever and the connected parts has not built up to a high level and only a thin coating 30 of elastomer is needed to reduce the shock to a comfortable level. The coating 30 not only makes the pliers more comfortable to the user but it also prevents damage to the pivot pins. When the pressure is released in a single stage, the full jaw pressure is available to accelerate the parts and when these parts are stopped in the full open position, the shock on the pivot pins has been sufficient to bend or break the pins.

In the second stage of opening, the operator merely releases his grip on the release lever 26 and the spring 10 moves the pliers to the full open position. While the motion in the second stage of opening is large, the forces are not great because this motion is effected by the tension spring 10.

Since only the portion of the elastomeric coating 30 adjacent the release lever 14 is effective in absorbing shock, it is possible to use elastomeric bumpers 31 on the under side of the hand grip section 28 of the release lever as shown in FIG. 4. The bumpers 31 is positioned so as to make contact with the release lever 14 when it reaches the first stage of opening indicated by the dotted line 29.

In FIGS. 5 and 6 the two stage opening is shown in connection with the pliers of the type shown in Pat. 2,997,903. As there shown, the handle 31 has a fixed jaw 32 at one end and at the other end has a generally rectangular section 33 on which is mounted a tiltable locking slide 34 which is biased to the left as viewed in

FIG. 5 by a tension spring 35 connected between point 36 on the slide and point 37 on a movable jaw 38 pivoted at 39 on the handle 31. The effect of the spring 35 is to close the jaw 38 on the stationary jaw 32 with an initial pressure which is determined by the tension of the spring 35. The jaw can be opened by grasping the slide 34 in the region indicated by the numeral 40 and sliding it backward or to the right as viewed in FIG. 5. Upon release of the slide, the spring 35 will automatically close the jaws of the work under light pressure. The full gripping pressure is developed by an actuating lever 41 of channel section pivoted at 42 on the movable jaw 38 and pivoted at 43 on a link 44 pivoted at 45 to the lower end of the slide 34. The pivot 45 is offset far enough from the center of the slide 34 so that a force to the right as viewed in FIG. 5 tilts the slide through an angle sufficient to case it to lock upon the handle section 33. As the actuating lever 41 is moved toward the closed position shown in FIG. 5, the pivot pin 43 which constitutes the knee of the toggle is moved to the dead center or full pressure position. In this position, a stop or projection 46 on the link 44 engages the bottom wall of the actuating lever 41.

The gripping pressure between the jaws is released by a release lever 47 of channel section pivoted on the pivot 43 and having an ear 48 which engages a shoulder 49 on the handle 31. To release the pressure, the hand grip section 50 of the release lever is squeezed, causing the ear 48 to cam the actuating lever to the release side of dead center. In this position shown in FIG. 6, the release lever 47 telescopes over and is in conforming engagement with the actuating lever 41 and the shock or impact of the initial or first stage opening is absorbed by an elastomeric coating 51 corresponding to the coating 30. This releases the pressure between the jaws but does not cause substantial opening. The momentum to be absorbed is accordingly small. The second stage of opening is effected by release of the hand grip portion 51 of the release lever 47, permitting the spring 35 to move the actuating lever 41 to the full open position indicated by dotted lines 52. Since the opening motion of the second stage takes place under the action of spring 35, the forces are relatively small compared to those developed during the initial stage of opening.

What is claimed is:

1. In a plier type toggle wrench having a handle with a stationary jaw at its front end, a movable jaw pivoted to said front end of the handle, toggle means for forcing the movable jaw toward the stationary jaw including an actuating lever having one end pivoted to the movable jaw and the other end with a hand grip section spaced from and opposite the back end of the handle, an adjustable abutment on the handle, a toggle lever having one end pivoted to the abutment and the other end

pivoted to the actuating lever between its ends, the movable jaw being forced toward the stationary jaw by squeezing the hand grip section of the actuating lever toward the handle to bring the common pivot between the actuating lever and the toggle lever into dead center relation with the other pivots, a release lever pivoted on the actuating lever for prying the hand grip section of the actuating lever away from the handle to bring the common pivot between the actuating and toggle levers to the release side of dead center remote from the handle, said release lever having a resilient bumper engaged by the actuating lever as the common pivot moves to said release side of dead center to absorb the momentum of the actuating and toggle levers.

5 15 2. The structure of claim 1 in which the release lever is squeezed toward the handle to pry the actuating lever to said release side of dead center.

20 2. The structure of claim 1 in which the bumper is positioned to engage actuating lever at a stage when the pressure between the jaws is substantially released but prior to substantial opening of the jaws.

25 25 3. The structure of claim 1 in which the bumper is positioned to engage actuating lever at a stage when the pressure between the jaws is substantially released but prior to substantial opening of the jaws.

4. The structure of claim 1 in which the pliers includes spring means urging the actuating lever away from the handle a further distance after engagement of the bumper whereby upon release of squeezing pressure applied to the release lever the actuating and toggle levers effect a further release of pressure between the jaws.

30 5. The structure of claim 4 in which the spring means causes movement of the jaws to the full open position.

35 6. The structure of claim 1 in which the release lever is of channel section adapted to telescope over the actuating lever, the forward end of the release lever being pivoted on the actuating lever and the back end of the release lever normally outstanding from the actuating lever in position to be squeezed against the release lever to pry the actuating lever to the release side of dead center.

40 7. The structure of claim 6 in which the bumper is a coating of resilient material on the back end of the release lever.

45 8. The structure of claim 1 in which the back end of the handle is threaded to receive an adjusting screw for positioning the adjustable abutment and a lock nut on the adjusting screw may be tightened against the back end of the handle to lock the adjustable abutment to the handle.
